UNITED STATES PATENT OFFICE.

ELIEL L. SHARPNECK, OF WINTHROP, MASSACHUSETTS, ASSIGNOR OF ONE-HALF TO HIMSELF, AND ONE-HALF TO FREDERICK W. MILLAY, OF HAVERHILL, MASSACHUSETTS.

HEEL-MOLD.

1,278,803.

Specification of Letters Patent. Patented Sept. 10, 1918.

Application filed April 21, 1916. Serial No. 92,612.

To all whom it may concern:

Be it known that I, ELIEL L. SHARPNECK, a citizen of the United States, residing at Winthrop, in the county of Suffolk and 5 State of Massachusetts, have invented new and useful Improvements in Heel-Molds, of which the following is a specification, reference being had to the accompanying drawings, forming part thereof.

10 This invention has reference to improvements in machines for manufacturing heels for boots and shoes.

One object of the invention is to provide an improved heel forming machine 15 from which the heel may readily be removed.

Other objects of the invention will appear from the following description.

The invention consists in the novel heel forming machine as will hereinafter be 20 more fully described and pointed out in the claim.

Figure 1, represents a plan view of the improved heel forming machine.

Fig. 2, represents a sectional view taken 25 on line 2—2 Fig. 1.

Fig. 3, represents a sectional view of the machine, on line 3—3 Fig. 1.

Fig. 4, represents the heel in side elevation.

30 Fig. 5, represents a front view of the same, and

Fig. 6 represents a top plan view thereof.

Similar characters of reference designate corresponding parts throughout.

35 As shown in Figs 1 to 3 inclusive of the drawing 10 indicates the base or bed of the machine which bed or base is adapted to be mounted on a work bench or on any similar support. At the upper portion of said bed 10 and preferably integral therewith is the form 11 having the upper inclined surface 12, the bevel edge 13 and the bevel edge 14 which latter conforms approximately to the shape of the top of the proposed heel and varies in width from the bevel 13 to the rear portion 15. Said base 10 has also the pins 16, 16 and, at one end, the posts or studs 17, 17 transversely slotted 40 near their upper ends and provided with 45 the key 18.

Pivotedly mounted on the base 10 is the mold member 19 having at one end a neck or extension adapted to be received between the studs or posts 17, 17 of said base 10. 50 This mold member 19 has the side exten-

sions 21, 21 and 22, 22 of which the former has sockets to receive the pins 16, 16. The inner wall of this mold member constitutes a mold chamber which conforms to the shape of the outer surface of the proposed heel and particularly having the curved surface 23 corresponding to the front or breast of the heel and meeting against the bevel 13 of member 11, and the downwardly flaring curved wall 24 the lower portion of 55 which embraces the edge 14 of said member 11 and coöperates therewith to constitute the bevel flaring channel 25. The upper smaller end of the mold chamber has a seat and is partially closed by the funnel and 60 guide member 27 which is seated in said seat and has the ears 28, 28 furnished with bolts or screws 29, 29 which are secured in screw threaded perforations of the mold member 65 extensions 22, 22.

In the bore of the guide member 27 is 70 slidably the plunger 30 which may be of any suitable length and, at its upper end has the ears 31, 31 between which is pivotally secured the pressure lever 32 one end of 75 which is pivotally connected with the link 33 and this link 33 is pivotally connected with a member of the neck of mold member 19.

With the parts of the machine in the positions shown in Fig. 1 lever 32 is first raised to withdraw plunger 30 from the bore of guide 80 member 27 clear of the upper funnel end of said bore. Material from which the heel is to be molded is now supplied to the mold 85 through the bore of the guide member 27 and a surplus of said material may extend into said bore to a height depending somewhat upon the compressibility of said material. This material is preferably of a consistency to be received in the channel of the 90 mold and may contain leather scraps or other wear resisting material and a binder the whole being adapted to be compressed 95 and to set or adhere to constitute a heel. 100

After the mold has thus been supplied with material, plunger 30 is replaced in the bore of guide member 27 and pressure is applied in a suitable manner to lever 32 to force 105 downward plunger 30 in order to effect the compression of the material. Such pressure may be gradually applied through said plunger 30 to permit the material in the mold to set or, after such pressure is applied, the molded heel may be retained in 110

the mold for a suitable period to permit the material to set sufficiently to retain its shape after removal of the heel from the mold.

When it is desired to remove the heel from the mold key 18 is withdrawn and that end of the mold member 19 having the neck is swung upward and, after a suitable point has been reached by such mold member 19 in its swinging movement, pressure is again applied to the lever 32 whereby plunger 37 acts to push the newly molded heel from the molding cavity of said member 19, the curve of the heel breast following the curve 23 of the mold somewhat and the heel swinging away from the mold wall 24. After the heel has thus been removed or pushed from the mold, the mold member 19 is swung back into place against this base 10 with its neck between the posts 17, 17 and the key 18 is replaced in the slots of said posts to hold said neck.

The product of said machine as a result of the above operation is the heel body shown in Figs. 4, 5 and 6 of the drawings which may be supplied with the usual wearing lift L indicated in Figs. 4 and 5. Such improved heel when made of suitable moldable material requires very little if any finishing and in some cases need not be covered. The shape of the heel is such that the heel breast a meets the flat seat b on a straight transverse line adapted to bear against a sole without the necessity of trimming said sole while the edges of said heel breast a

extend upward at the sides of the seat b to 35 form the ends e, c of the upstanding flaring lip d which conforms exteriorly to the shape of the heel and interiorly to the shape of the seat b whereby said lip d is adapted to confine and finish the edge of that portion of a 40 sole seated in or on said seat b without the necessity of unduly skiving the edge of said sole.

By such molding process I am able to construct a heel having the seat b and the lip d 45 integral with said seat and with said heel without cutting the heel and I find that the lip d when molded as an integral part of the heel and its seat is stronger and more desirable than when said lip is formed by cutting 50 away the material within the line of said lip.

Having thus described my invention I claim as new and desire to secure by Letters Patent—

The combination with a base having an upstanding form having a bevel edge, of a mold member mounted on said base and having a heel shaped cavity one end of which receives said form, means to pivotally connect said mold member and said base, a funnel guide mounted at the other end of said cavity, a plunger slidable in said guide, a lever connected with said plunger, and a pivoted link connecting said lever and 60 said mold member.

ELIEL L. SHARPNECK.
